[57] CLAIM

The ornamental design for an enclosed baby carriage, as shown and described.

DESCRIPTION

FIG. 1 is a side elevation view of an enclosed baby carriage showing our new design;

FIG. 2 is a side elevation view of the side opposite that shown in FIG. 1 thereof;

FIG. 3 is a left end elevation view thereof;

FIG. 4 is a reduced top plan view thereof;

FIG. 5 is a reduced bottom plan view thereof;

FIG. 6 is a reduced right end elevation view thereof; and

FIG. 7 is a perspective view of the enclosed baby carriage shown in open condition.
